UNITED STATES PATENT OFFICE

171,179

LAMP BASE

Marion Axelrod, East Gloucester, Mass.

Application April 22, 1953, Serial No. 24,631

Term of patent 7 years

(Cl. D48—20)

To all whom it may concern:

Be it known that I, Marion Axelrod, a citizen of the United States of America, residing at East Gloucester, county of Essex, and Commonwealth of Massachusetts, have invented a new, original, and ornamental Design for a Lamp Base, of which the following is a specification, reference being had to the accompanying drawing, forming a part thereof.

Fig. 1 is a front elevational view of a lamp base showing my new design;

Fig. 2 is a top plan view thereof to a larger scale, the broken lines indicating a harp and socket being omitted for convenience of illustration; and

Fig. 3 is a side elevational view thereof but with

the top portion of the broken lines indicating a harp and the top piece extending above the harp being omitted since these features are shown in Fig. 1.

I claim:

The ornamental design for a lamp base, substantially as shown and described.

MARION AXELROD.
